(57) **CLAIM**

The ornamental design for a sheet of writing paper, as shown.

DESCRIPTION

FIG. 1 is a front plan view of a sheet of writing paper showing my design; and,

FIG. 2 is a back plan view thereof.

FIG. 1 depicts an adequately printed series of arcuate lines evenly spaced on the vertical axis of the front of the sheet of writing paper, each of which has a gap or space near the far left edge.

FIG. 2 depicts an adequately printed series of horizontal straight lines evenly spaced on the vertical axis of the back of the sheet of writing paper, each of which is divided by a series of evenly spaced gaps or spaces.
